1.28 : Perspective

1.1 is a top, front and right side perspective view of a delivery robot embodying our new design, showing a first state of use when the delivery robot is not operated; 1.2 is a front view thereof; 1.3 is a rear view thereof; 1.4 is a left side view thereof; 1.5 is a right side view thereof; 1.6 is a top plan view thereof; 1.7 is a rear and right side perspective view thereof; 1.8 is a top, front and right side perspective view of the delivery robot showing a second state of use in which the front door of the delivery robot has been opened; 1.9 is a front view thereof; 1.10 is a rear view thereof; 1.11 is a left side view thereof; 1.12 is a right side view thereof; 1.13 is a top plan view thereof; 1.14 is a top, front and right side perspective view thereof; 1.15 is a top, front and right side perspective view of the delivery robot, showing a third state of use in which the open front door of the delivery robot has been descended; 1.16 is a front view thereof; 1.17 is a rear view thereof; 1.18 is a left side view thereof; 1.19 is a right side view thereof; 1.20 is a top plan view thereof; 1.21 is a top, front and right side perspective view thereof; 1.22 is a top, front and right side perspective view of the delivery robot, showing a fourth state of use in which the wheel driver of the delivery robot has been stretched forward as compared to 1.1; 1.23 is a front view thereof; 1.24 is a rear view thereof; 1.25 is a left side view thereof; 1.26 is a right side view thereof; 1.27 is a top plan view thereof; and 1.28 is a rear and right side perspective view thereof. This article can be used for a delivery robot of which the front door can be opened and the open front door can descend. This design is for a heavyweight article and therefore the bottom part of the article is omitted. The reflections and shadows shown in all reproductions are disclaimed.

The broken lines shown in the figures are for the purpose of illustrating portions of the delivery robot and form no part of the claimed design.
